United States Patent Office.

GEORGE W. MANSON, OF NEW YORK, N. Y., ASSIGNOR TO CHARLES M. VANDERVOORT AND WILLIAM F. FLUHRER, OF SAME PLACE.

Design No. 4,303, dated August 23, 1870.

DESIGN FOR A HAIR-PIN.

The Schedule referred to in these Letters Patent and making part of the same.

To whom it may concern:

Be it known that I, GEORGE W. MANSON, of the city, county, and State of New York, have invented a new and original Design for Hair-Pins, of which the following is a specification, reference being had to the accompanying drawing.

The design consists of a hair-pin, the legs of which are so shaped as to be brought in contact with each other at the point *a*, near the ends.

The ends *b* are bent outward, so that they may enter the hair easily.

Above the point *a* each leg of the pin is corrugated, as shown at *c*, and these corrugations may be duplicated, if desired, or three or more corrugations may be formed on each leg.

The object of bringing the legs of the pin together at the point *a* is to cause the pin to shut upon the hair,

and to clasp it with a spring-like action, so as to retain the hair which is held in the loop *d* of the pin, and which, by its weight, might otherwise draw the pin from its place.

The corrugations *c* serve to enable the pin to take a firmer hold upon the hair, and to thus support in place the mass of hair held in the loop *d*.

What I claim, and desire to secure by Letters Patent, is—

The design for hair-pins, substantially as herein shown and described.

In testimony whereof I have signed my name to this specification before two subscribing witnesses.

GEO. W. MANSON.
